UNITED STATES PATENT OFFICE

WALTER M. CROSS, OF KANSAS CITY, MISSOURI, ASSIGNOR, BY MESNE ASSIGNMENTS, TO GASOLINE PRODUCTS COMPANY, INC., OF WILMINGTON, DELAWARE, A CORPORATION OF DELAWARE

HEAT EXCHANGER

Application filed May 12, 1924. Serial No. 712,845.

This invention relates to improvements in heat exchangers, and refers more particularly to a construction which provides for an increased heat exchange between mediums 5 circulated in radiating contact.

Among the objects of the invention are, to provide a construction whereby a medium, such as a fluid either liquid or gas, is circulated through hollow members such as a continuous tube or conduit while externally of this member is circulated a second medium which has a relatively different temperature than the first medium and which is circulated thereabouts in order to either supply 10 heat to the internally circulated medium or extract heat therefrom. For example, such constructions may be mentioned as heating coils positioned in a furnace or heating means where a hot combustion gas is circulated about tubes or coils, heat exchangers where gases or liquids are brought in radiating contact, condensers or water tube boilers and other constructions of a similar type. In the drawings the construction is shown as 15 applied to a continuous coil positioned in a furnace, particularly adapted for the conversion of hydrocarbon oil which is circulated through the coil and is heated by the combustion gases of the furnace supplied by 20 burners.

In the drawings:

Fig. 1 is a side elevational view of the apparatus with parts broken away and parts shown in section.

Fig. 2 is a view taken along the line 2—2 in Fig. 1.

Referring to the drawings, 1 designates the side walls of a furnace 2 which encloses a plurality of tubes 3 connected in series by 40 headers or tube fittings 4 to form a continuous conduit or passage for the liquid which is circulated therethrough. Upon the outer surface or periphery of the respective tubes are formed corrugations 5 which serve to 45 expose an increased surface and facilitate and promote the heat exchange between the combustion gases and the liquid medium passing through the tubes. These corrugations transmit an increased amount of heat 50 to the medium circulated through the con-

duit extracting the heat from the combustion gases thereby permitting much more rapid heating than where the medium is circulated through a plain smooth pipe coil without the absorption rings. 55

The combustion gases supplied by a burner diagrammatically shown at 6 find their way through the checkered brickwork furnace arch 7 and rise upward around the respective tubes directed in their passage by the absorption rings 5 and the chamfered obstructions 8 positioned in the side walls of the furnace to turn aside or deviate the gaseous medium in its travel and to increase the friction which, when additional pressure is produced by a stronger draft, increases the speed at which the heating medium is traveling in its passage through the furnace. The chamfered construction of the protuberances or protrusions 8 adds to the resistance offered by the walls of the tube chamber and creates a slight turbulence in the gaseous products of combustion on their flow therethrough, preventing the formation of a blanket of gas on the walls of the tube chamber. It will be appreciated that the action of the chamfered obstructions 8 facilitates the rate of heat exchange. The interior construction is carefully arranged and figured to provide passageways for the heating medium about the tubes of the same size, contour 70 and of substantially the same deviation of travel. 75

This arrangement produces a uniform friction to the gases and increases thereby the efficiency of the apparatus due to the increased heat exchange which is effected. When the grouping or the collocation of the members has been properly distributed, the temperature differential between the mediums circulated internally and externally of the tubes may be greatly decreased making for a substantial increase in the efficiency of the heat exchanger construction. 80

As mentioned, this arrangement of the elements to provide for the setting up of a uniform friction against the passage of the medium, prevents short-circuiting and produces a more efficient heat exchange. The gases 85 in their travel proceed through passageways 90 to

of a like size, contour and all of such passageways have substantially an identical deviation of travel whereby the different portions of the gases are subjected to a uniform friction.

5 The novelty of the invention lies primarily in a construction designed to impose upon the externally circulated medium a relatively uniform friction eliminating short circuiting of any portion thereof thereby increasing the efficiency of the heat exchangers. In a construction of this character, the temperature differential between the mediums circulated in radiating contact is materially reduced with relation to constructions heretofore utilized.

10 The absorption rings or discs fill in the space between the tubes thereby constricting the openings through which the external medium is circulated which increases the friction of the medium and promotes a relatively better heat transfer when the velocity or speed of the medium is raised. Where plain tubes are utilized and connected into 15 end fittings or headers, it is impossible, due to the character of these end fittings, to place the tubes close enough together to sufficiently constrict the openings and thereby improve the heat transfer in the same manner in which 20 the absorption rings may be utilized. For example, where plain tubes are used and where the number of square feet of heating surface is the same as a construction in which the absorption rings or discs are used, a difference of from 15% to 20% economy in fuel 25 consumption is effected where the absorption rings are used, due to the better heat transfer occasioned by the increased speed of the products of combustion produced by forcing the 30 draft and by constricting the passageways due to the filling-in effect between the tubes of the absorption rings.

35 The pressure differential and element indicative of the speed of the combustion gases between the top and the bottom of the furnace or combustion chamber in the specific construction described amounted to as much as one-half inch of water.

40 I claim as my invention:

45 1. A heater construction comprising a chamber, adapted to contain products of combustion, a checker brick partition forming the roof of said chamber and the floor of a tube chamber, and adapted to distribute 50 the products of combustion evenly in said tube chamber, a plurality of tubes positioned in said tube chamber above said partition, said tubes being arranged in staggered 55 relation, the walls of said tube chamber being provided with abutments projecting 60 therein to effect an efficient exchange of heat from products of combustion of said tubes.

65 2. A heat exchange device comprising a chamber, a plurality of members within said chamber adapted to contain a fluid medium,

means for passing a heating fluid through said chamber, protuberances upon the interior wall of the chamber, means associated with said chamber to evenly distribute the heating fluid through the chamber, the members within the chamber and the protuberances upon the wall being so positioned as to produce a uniform retardation and circuitous flow of the heating fluid circulated externally of said members.
